UNITED STATES PATENT OFFICE.

MILFORD G. CHANDLER, OF CHICAGO, ILLINOIS, ASSIGNOR, BY MESNE ASSIGNMENTS,
TO CURTIS B. CAMP, TRUSTEE, OF OAK PARK, ILLINOIS.

CARBURETOR.

Application filed July 1, 1920. Serial No. 393,229.

This invention relates to carburetors of the type for lifting fuel from a low level supply source to the level of the carburetor.

In carburetors of the vacuum feed type, it is important that the suction or depression in the body of the carburetor and in fact in all parts of the induction passage to the engine supplied by the carburetor, be kept as low as consistent with the functions to be performed by that suction. In non-fuel lifting carburetors, this suction ordinarily performs but two functions; that of atomizing the fuel and that of properly proportioning the fuel to the amount of air. In a fuel lifting carburetor, however, a third function of lifting fuel from a low level supply to the level of the carburetor must be performed by this suction. The carburetor of my invention is so constructed that although the suction required for lifting fuel may be as high as the equivalent of 40 inches of gasoline in a manometer tube, nevertheless the suction in the body of the carburetor may continue to be as low as the equivalent of only 18 to 20 inches of gasoline in a manometer.

The results above named are accomplished by means of an arrangement of Venturi tubes, one of which delivers fuel into the mixing chamber of the carburetor, another one of which creates the suction for lifting fuel to the float chamber of the carburetor, and a third which is in the form of an expanding Venturi tube serves to create suction upon the discharge end of the nozzle Venturi tube to aid in the atomization of the fuel and in the suction produced by the nozzle Venturi tube.

My invention is illustrated in the accompanying drawings in which like characters represent like parts through the several views.

Figure 1 is a vertical section through the main induction passage and nozzle showing the float chamber in outline.

Figure 2 is a section through the float chamber and induction passage taken at right angles to the sections of Figure 1.

Figure 3 is an elevation of the body portion of the carburetor with the float chamber removed.

Figure 4 is a detail showing the method of controlling the suction and method of adjustment of the suction producing Venturi tube, and

Figure 5 is a partial elevation of the shoe showing the suction controlling cam.

Figure 6 is a vertical section through the fuel passage from the float chamber to the nozzle Venturi tube.

In accordance with my invention, the body 8 and float chamber 9 are separable at 10 and so connected by means of a screw 11 that the float chamber may be turned at any angle to the body for operating the carburetor either as a vertical or horizontal instrument. The body portion 8 is internally bored to a gradually tapering shape but has a cylindrical portion 12 adjacent the engine in which the throttle 13 is mounted on the shaft 14. The main casting for the body 8 is provided with two parallel spaced wings 16. These wings together with a separable spacing bridge member 18 forms a housing in which the pivoted shoe 19 operates. One face of the shoe 19 constitutes a wall of the induction passage 20 while the side walls 21 of the shoe 19 are machined to fit between the two wings 16 with only a few thousandths of an inch clearance so that the shoe will constitute a piston-like wall substantially closing one side of the box formed between the wings 16 and the bridge 18. The external surface 22 of the shoe 19 is formed cylindrically so that it may operate with slight clearance of the similarly machined surface 23 of the bridge. A packing strip 24 with suitable spring 25 may be used for sealing the space between the shoe and the bridge so that machining a close fit will be unnecessary. The shoe 19 is preferably rigidly attached to a pivot pin 27 inserted through openings 29 in the wings 16. A small hole 30 affords communication between the restricted portion of the induction passage and the space behind the shoe 19. A spring 31 extends between the bridge 18 and a boss 32, carried on the shoe 19 which is preferably provided with a cup 33 to prevent lateral distortion of the spring due to a change in angle of the shoe.

A nozzle 36 having Venturi shape, is located at an angle to the axis of the main induction passage and has its discharge end 37 situated in the region of high suction in the induction passage for all positions of the shoe 19. This nozzle is provided with fuel delivery openings 39 which receive their fuel from an annular passage 40 which com-

municates with the lower part of the float and fuel chamber through a hole 40⁵ an internal bore in the screw 11 and a passage in the casing in which the needle valve 41 seats. The nozzle Venturi tube preferably has its external end open to atmosphere, though the arrangement is such that a hot air tube leading from a jacket around the exhaust pipe may be connected into the portion of the housing in which this Venturi tube is located.

A vacuum producing Venturi tube 43 shown in detail in Figure 4 is mounted in a close fitting cylindrical opening in a boss 44 which extends outwardly from one of the wings 16. The opening through this Venturi tube is eccentric to the external cylindrical surface of the member 43 so that by rotation the position of the opening may be changed.

Within or upon one wall of the shoe 19 is a cam 45 forming one edge of a slot which communicates with the induction passage of the carburetor. This cam—or cam shaped edge of the slot—is eccentric to the pivot of the shoe. It overlies the edge of the opening of the inner end of the vacuum Venturi tube 43 and is shaped to suit the engine, and to provide a suitably varying obstruction to the flow of air through the vacuum Venturi tube 43 for different positions of the shoe 19, depending upon the amount of air being drawn into the carburetor. The slot may be considerably wider than shown in the drawings, since the other edge of the slot is not calculated to function in varying the air passage through the vacuum Venturi tube. As pointed out above, the rotation of the vacuum Venturi tube 43 will cause its inner opening to be obstructed to a greater or less degree by the edge of the cam 45, thereby providing an initial adjustment of the degree of restriction, which degree of restriction is further controlled by the movement of the shoe 19 and the shape of the cam 45. The construction of the carburetor inherently requires that the suction in the mixing chamber of the carburetor must slightly increase with increased flow of air. This increased suction in the induction passage of the carburetor creates an increased suction in the passageway bounded by the cam 45 and would create a proportionate increased flow of air through the Venturi tube 43 were it not for the cam 45 which, as illustrated in Figure 5, is shaped so that the discharge opening from the Venturi tube 43 is more limited in size under the conditions which provide greater induction passage suction.

The throat of the Venturi tube 43 is connected through registering passages 48, 50 and 51 with the upper spaces of the float chamber for providing an enhanced suction or depression therein for lifting fuel. By

experimentally contouring the edge of the cam 45, the suction in the float chamber may be maintained constant for all positions of the shoe 19, or may be caused to either increase or decrease as the shoe 19 moves to its wider open position. This arrangement permits of an accurate control of the fuel feeding differential between the float chamber and the nozzle openings 39 so that the desired ratio of fuel and air may be maintained under all conditions. A lever arm 52 is connected with a dash control (not shown) for rotating the Venturi tube 43, and by means of this the suction in the float chamber may be varied to produce a varied differential between float chamber suction and manifold suction, so as to increase or decrease the general richness of the mixture throughout the whole range of operation. Experience shows that for cold starting the mixture must be richer than for the best running conditions after the engine is heated up.

It is occasionally necessary that the suction in the float chamber be temporarily increased beyond that necessary for ordinary driving. This happens when an automobile, having a tank at the rear ascends a very exceptional grade such, for example, that the lift between the rear tank and the carburetor exceeds 40". In order that under these conditions the suction will be automatically increased, a ball valve 53 is provided in a float chamber cover normally sealing the opening between atmosphere and the duct 54 leading through passage 55 to the space back of the shoe 19. A pin 56 fits closely in an opening through the float chamber cover and is adapted to be engaged by a collar 57 carried by and rising and falling with the float chamber valve stem 58 as the fuel raises and lowers in the float chamber. This pin 56 is adapted when raised by the dropping of the fuel in the float chamber, to push the ball 53 off its seat and thus open a communication between atmosphere and the space back of the shoe 19. The opening 30, through the shoe 19, is relatively small so that when the ball 53 has raised off its seat by the lowering of the fuel in the float chamber, the suction back of the shoe 19 will be somewhat relieved, causing the shoe to assume a position more nearly enclosing the induction passage, thus causing the suction in the mixing chamber to be increased, and consequently increasing the suction in the carburetor float chamber. When this suction in the carburetor float chamber has been increased sufficiently to cause fuel to be drawn into the float chamber, the float again rises permitting the ball 53 to become either fully or partially seated. The passage around the ball 53 is outwardly flared such that the area of the opening past the ball

is greater as the ball is moved to a greater distance off its seat. When under some extreme condition the normal float chamber suction is insufficient to lift fuel from the 5 low level source into the float chamber, then the level of the fuel will drop slightly in the float chamber. In so doing, the float will also drop until the ball 53 has been raised off its seat just enough to create sufficient 10 suction to bring fuel into the float chamber at a rate proper to maintain the new low level therein. If the lift to the float chamber becomes still greater, then the fuel will drop still lower and the ball 53 will be moved still farther off its seat and a new balance will be found. The variation in 15 fuel level in the float chamber will be almost negligible, however, since the relation of the parts is such that a very small change in 20 level in the float chamber effects a considerable change in the size of the passage around the ball 53.

Assuming an engine to be idling, that is, operating with throttle 13 substantially 25 closed, the suction in the mixing chamber 20 is insufficient to cause the shoe 19 to be moved materially off its normal position in which it substantially closes the air induction passage. Therefore all of the air for 30 idling must enter through the fuel feeding Venturi tube 36 and the suction producing Venturi tube 43. These two tubes are so proportioned that for the idling condition their restriction will be sufficient to create a float 35 chamber suction of between 30 and 40 inches of gasoline in the manometer tube. The needle valve 41 provides just the proper restriction so that the suction created at the nozzle openings 39 in the Venturi tube 36 is just enough greater than the suction on the 40 fuel in the float chamber to deliver the proper proportions of fuel and air.

As the throttle 13 is opened and the engine demand is increased, the suction in the mixing chamber 20 increases, thus creating a greater suction in the space behind the shoe 19 and thus causing the shoe to open proportionately to the engine demand. 45 The fact that the opening 30 is located at a point of high local suction in the induction passage causes the shoe to move in response to very slight increases in suction in the mixing chamber 20, notwithstanding the increase in resistance offered by the spring 31 as the shoe is opened.

At the highest engine demand, that is, with wide open throttle and comparatively 50 low speed, the shoe 19 opens to a position in which the passageway through the carburetor is quite free but on account of the large flow of air at this time, the suction in the mixing chamber is increased to the equivalent of 25 to 30 inches of gasoline in the 55 manometer tube, and since the point of

greatest restriction in the intake passage is at the discharge end of the nozzle Venturi tube 36, the suction on that tube increases to a very much greater degree than the suction in the larger portions of the intake 70 passage. In fact, it is found that with a suction of 25" of gasoline in the mixing chamber at a point just anterior to the throttle, the suction at the discharge end of the Venturi tube 36 is equivalent to 45 to 50" 75 of gasoline and the suction at the throat of the nozzle Venturi at which point the gasoline is delivered into it is still higher. This increase in suction provides the increased amount of fuel necessary to be mixed with the incoming air to maintain proper proportions of gasoline and air under the condition of greater fuel demand. If the proportions are not absolutely correct, they 80 may be varied by shaping the cam 45 to provide either greater or less suction in the float chamber as conditions demand.

While my invention is described in connection with the details illustrated in the accompanying drawings, it is to be understood that I do not wish to be unduly limited thereto, certain modifications being possible without departing from the spirit and scope of my invention.

I claim:

1. A carburetor comprising in combination a casing forming an induction passageway, a movable shoe pivoted in said casing forming one wall of the induction passage, 100 and a Venturi tube constituting a fuel nozzle supported in said casing and situated at an angle to the axis of the induction passage and inclined in the direction of the air flow therethru with its discharge end adjacent said shoe when the shoe is in its normal position, the shoe being conformed to fit about the end of the Venturi tube, and substantially parallel with the Venturi tube at the end thereof when in its normal position for providing an arcuate restriction of the induction passage when the shoe is in its normal position.

2. In a carburetor, the combination with a casing forming an induction passage, of a movable shoe within said casing, a suction producing Venturi tube extending through said casing and having its discharge end terminating adjacent the side of said shoe, said shoe being provided with a cam to control the area of the discharge opening of said Venturi tube, and means for delivering fuel to said induction passage.

3. In a carburetor, the combination with a casing forming part of an induction passage, of a shoe pivoted in said casing and forming a wall of said induction passage, a cam formed in said shoe, a Venturi tube extending through said casing and having its inner end terminated adjacent said cam,

- said Venturi tube being eccentrically mounted and adapted to rotate to present greater or less of its opening to the action of said cam, and a duct connecting the throat of said Venturi tube with the upper spaces of a fuel reservoir, and means for delivering fuel from the lower part of the reservoir to the induction passage.
4. In a carburetor, the combination with a casing, of a pivoted shoe mounted in said casing, a housing enclosing the side of said shoe away from the induction passage of the carburetor, an opening between the space behind said shoe and the induction passage of said carburetor to create a suction behind the shoe for moving the same, a float chamber, a float in said chamber, and a valve in said float chamber operated by the float therein, and adapted to be unseated when the float descends, said valve, when opened, affording communication between the atmosphere and the space behind said shoe, and means for delivering fuel from the float chamber into the induction passage.
5. In a carburetor, the combination with an induction passage, of a fuel chamber, means connecting the upper part of the fuel chamber with the induction passage for creating a suction in the fuel chamber for lifting fuel thereto which under some conditions is greater than the suction in the induction passage, a Venturi tube constituting a fuel nozzle discharging into said induction passage and lying adjacent a stationary side thereof, and a movable member constituting a side of said induction passage and so shaped as to substantially seal the communication between external atmosphere and the induction passage around the inner end of the said Venturi tube when the movable member is in normal position, said member being adapted to be moved by the suction in the induction passage to open and enlarge the communication between atmosphere and the induction passage around the inner end of said Venturi tube, but being so shaped that for all of its positions the region of highest suction is close to the inner end of the Venturi tube.
6. In a carburetor, the combination with a casing forming an induction passage of a stationary side wall, and an opposite movable side wall for said induction passage, a wall enclosing the space behind said movable side wall, the movable side wall being so shaped as to constitute with the stationary side wall a gradually expanding induction passage, the restricted portion of which is enlarged by the movement of the movable side wall away from the stationary side wall, a hole communicating between the induction passage and the space behind the movable side wall, said communication terminating in the induction passage near the region of greatest suction therein, and means for delivering fuel into the induction passage.
7. In a carburetor, the combination with an induction passage of a secondary air inlet therefor, a chamber in suction communication with the induction passage, a movable wall for said chamber controlling in its movement the size of the opening through the secondary air inlet, an atmospheric inlet for said chamber, a valve controlling said inlet, said valve when opened serving to relieve the suction in said chamber to an extent sufficient to partially close the opening through the secondary air inlet, and means to deliver fuel to said induction passage.
8. In a carburetor, the combination with an induction passage of a secondary air inlet therefor, a chamber in suction communication with the induction passage, a movable wall for said chamber controlling in its movement the size of the opening through the secondary air inlet, an atmospheric inlet for said chamber, a valve controlling said inlet, a fuel reservoir, a float in said reservoir, and connecting means between said float and said valve for opening the atmospheric communication to said chamber when the float in the reservoir falls below a predetermined level, and means to deliver fuel from the fuel reservoir to the induction passage.
9. In a carburetor, the combination with an induction passage of a fuel reservoir receiving suction from the induction passage for lifting fuel to the fuel reservoir, means for delivering fuel from the fuel reservoir to the induction passage, a secondary air inlet for the induction passage, a chamber in suction communication with the induction passage, a movable wall for said chamber controlling in its movement the size of the opening through the secondary air inlet, an atmospheric inlet for said chamber, a valve controlling said inlet, a float in the fuel reservoir, connecting means between said float and said valve for opening the atmospheric communication to said chamber when the float in the reservoir falls below a predetermined level, whereby the wall of said chamber is moved and the entrance to the induction passage is restricted and the suction in the induction passage is increased, the suction connection between the induction passage and the fuel reservoir serving, under these conditions to provide an increased suction in the fuel reservoir for lifting fuel thereto through a greater height, the opening past the valve in said atmospheric inlet being proportioned so that the degree of increased suction in the induction passage will be only sufficient for lifting fuel to the fuel reservoir in such quantities as is necessary for raising the float to a substantially predetermined level.
10. In a carburetor, the combination with an induction passage, of a Venturi tube ex-

tending into said passage, a fuel chamber, a duct connecting the restricted part of said Venturi tube with the upper space of said fuel chamber, a member automatically movable in response to engine demand, a cam movable with said member, said cam being arranged to pass opposite the inner end of said Venturi tube, and to variably obstruct the discharge opening from said Venturi tube into the induction passage by overlapping the discharge opening from said Venturi tube different amounts for different engine demands, and a nozzle for delivery of fuel from the fuel chamber into the induction passage.

In witness whereof, I hereunto subscribe my name this 23rd day of June, 1920.

MILFORD G. CHANDLER.
